UNITED STATES PATENT OFFICE.

JAMES W. BEVANS, OF WASHINGTON, DISTRICT OF COLUMBIA.

TOY BOOK.

961,675.

Specification of Letters Patent. Patented June 14, 1910.

Application filed January 20, 1910. Serial No. 539,077.

To all whom it may concern:

Be it known that I, JAMES W. BEVANS, a citizen of the United States, residing at Washington, in the District of Columbia, 5 have invented new and useful Improvements in Toy Books, of which the following is a specification.

This invention relates to improvements in toy books and the object is to produce a 10 book so arranged that it may be converted into a toy theater, doll house or other device or representation and the pages utilized to form the successive scenes of the theater or the different rooms of the doll-house, combined with cut-out objects, characters, etc., 15 to be used in connection with the theater or doll-house, the whole forming a complete book.

With the above object in view, the invention 20 consists in the novel features of construction hereinafter fully described, particularly pointed out in the claims, and clearly illustrated by the accompanying drawings, in which—

25 Figure 1 is a view of a book constructed in accordance with my invention, the same being shown with the leaves or pages partly separated; Fig. 2, a fragmentary view showing the detachable pages containing the 30 cut-out pictures; Fig. 3, a perspective view showing the book opened and arranged to form a toy-theater; Fig. 4, a vertical transverse sectional view showing one of the 35 pages raised preparatory to forming one of the scenes; Fig. 5, a perspective view partly in section showing one page partly raised to change the scene; Fig. 6, is a sectional view taken through the closed book. Fig. 7, a 40 fragmentary view showing a portion of one of the cut-out pages; Fig. 8, a view showing one of the cut-out characters, and Fig. 9, a view of one of the cut-out wings.

I have illustrated my invention in one of its forms, namely, that of a theater-book, 45 but I do not so limit it as it may be embodied in many other forms, as will more fully appear hereinafter.

The book consists of the front cover 1 and the back cover 2, and a series of pages or leaves 1^a, 1^b, 1^c, and a series of pages or leaves 2^a, 2^b, 2^c, of which pages or leaves there may be any desired number, the pages and covers being hinged together as in any ordinary book. The front cover 1 may have 55 upon its outer side the title of the book or play, and any preferred illustrative or deco-

rative matter, and upon its inner side, directions for the use of the book as a toy-theater or doll-house. The series of leaves or pages 1^a, 1^b, 1^c immediately following the 60 cover 1 are arranged to be detached, being perforated at their inner edges as illustrated in Fig. 2, and they contain the pictures to be cut out. If the book is to be used as a doll-house, these pictures would comprise 65 representations of furniture, dolls, dresses, etc. In the book illustrated, they consist of the characters of the play, the wings 3, the curtain-strip 4 and the base-strip 5. The characters, as illustrated in Fig. 8, have 70 elongated base-strips 6 which are bent to form substantially triangular-shaped bases, the contacting portions 7 of the opposite ends of the base-strip being united by pasting or otherwise. Thus a firm supporting- 75 base for the character or object is provided. The wings 3 are formed with projecting- portions or tongues 8 to engage in slots formed in the hinged portions of the leaves or pages 2^a, 2^b, 2^c presently to be described. 80 The series of pages 2^a, 2^b, 2^c and the back- cover 2 have each, folding- portions or hinged sections 9 at their side edges which are normally folded inward upon said leaves or pages. One face of the leaves 2^a, 2^b, 2^c, 85 and their hinged sections 9 contains a continuous scene or representation, as well as the inner faces of the back-cover and its hinged sections. The outer face of the back-cover and its hinged sections contain a rep- 90 resentation of the exterior of a theater. The opposite face of each page 2^a, 2^b, 2^c to that having the scene thereon, has a ground scene for a portion of its width and the re- 95 presentation of the floor of the stage for the remainder of its width. The faces of the hinged sections on the side opposite to that containing the scene, carry reading matter, being the story of the play.

In using the book as a toy-theater, said 100 book is placed flat on the table with the back-cover 2 uppermost. This back-cover is then raised to vertical position and the hinged sections 9 thereof swung out at right-angles thereto. Thus there is presented 105 three sides of a theater. The outer face will be the exterior of the theater and the inner face, the first scene of the play. The side of the next leaf or page uppermost will contain a representation of the ground for 110 the scene displayed and a portion of the floor of the stage. The hinged sections 9 of

the back-cover are wider than those of the pages or leaves 2^a, 2^b, 2^c and the scene displayed thereon is only equal in width to the width of the scenes displayed on the hinged sections of the other pages and the width of the ground-scenes. The portions 10 of the hinged sections 9 of the back-cover extending beyond the scene displayed thereon, carry the representation of theater-boxes and this portion of said hinged sections is equal in width to the representations of the portions of the floor of the stage carried by the leaves or pages 2^a, 2^b, 2^c. These hinged sections 9 of the back-cover are not disturbed in the setting of the several scenes of the play and as they are wider than the other hinged sections 9, the representations of the theater-boxes are displayed throughout the entire play. A base-strip 5 may be provided having notches to receive and support the lower forward ends of the hinged sections 9 of the back-cover, this base-strip forming one of the cut-out objects. The hinged sections 9 of said back-cover are connected at their upper forward edges by a curtain-strip 4 suitably notched and having thereon the representation of a portion of a curtain, this strip being also one of the cut-out objects. The scenes are set by inserting the projecting portions 8 of the cut-out wings 3 in slots 13 in the hinged sections 9 of the back-cover and the leaves or pages 2^a, 2^b, 2^c. The proper characters for each scene are drawn across the stage by cords 35 or threads attached to the bases thereof. To change the scenes, the characters and wings 3 are removed, and the next page raised and its hinged sections 9 opened out, new wings 3 placed in position and that act of the play 40 performed. Before swinging up the page for the next scene, the hinged sections 9 of the page just used are folded inward flat against the latter page. Each page when set as a scene holds the pages that have been used, from dropping down, and one side of each page forms the ground scene for the scene represented on the preceding page. In order to provide a ground-scene for the last scene, a separate leaf 14 is provided 45 having no hinged sections.

It will be seen that I have provided a book which may be used as a toy-theater and the story contained in the book enacted as a play, and that there is combined, cut-out pictures, a story book and a theater. The child not only can read the story but make characters, by cutting out the pictures, and then actually produce the story as a play. The device does not lose the character of a book and is attractive in appearance and simple and compact. All of the well-known fairy-stories or child-hood stories could be embodied in the form of books comprising my invention and by changing the representation of the exterior of a theater to that

of the exterior of a house and the several scenes to the various rooms, of a house, a very attractive doll-house in book-form would be provided.

Having thus fully described my invention what I claim as new and desire to secure by Letters Patent of the United States, is:—

1. A toy book having leaves pivoted at one edge in book-fashion and carrying at their side-edges, pivoted sections adapted to be swung out at right-angles thereto, each leaf and its side-sections when the latter are unfolded, forming with the adjacent leaf, a compartment or inclosure having a bottom, end-walls and side-wall. 75

2. A toy book having covers and leaves pivoted therein in book-fashion, one of said covers having pivoted side sections adapted to be swung out at right-angles thereto when said cover is raised at right-angles to the other cover, said leaves carrying representations adapted to be successively displayed in the compartment or inclosure thus formed. 80

3. A toy book having covers, leaves pivoted therein in book-fashion having pivoted side-sections adapted to be swung out at right-angles thereto, one of said covers having pivoted side-sections adapted to be swung out at right-angles thereto when said cover is raised at right-angles to the other cover, 90 said leaves and sections carried thereby carrying representations adapted to be successively displayed in the compartment or inclosure thus formed. 95

4. A toy book having covers, and leaves pivoted therein in book-fashion, one of said covers having side-sections pivoted thereto adapted to be swung out at right-angles thereto when said cover is raised at right-angles to the other cover, said cover and side-sections having on the outer sides thereof, the representation of the exterior of a building, and said leaves carrying representations adapted to be successively displayed in the inclosure or compartment thus formed. 100

5. A toy book having covers, and leaves pivoted therein in book-fashion, said leaves and one of said covers having pivoted side-sections adapted to be swung out at right-angles thereto, the side-sections of the cover 115 projecting beyond those of the leaves. 110

6. A toy book having covers, and leaves pivoted therein, certain of the leaves having side-sections pivoted thereto and adapted to be swung out at right-angles thereto and others of the leaves having cut-out representations thereon, one of the covers having pivoted side-sections adapted to be swung out at right-angles thereto when said cover is raised at right-angles to the other cover, 120 and said leaves and side-sections carried thereby carrying representations adapted to be successively displayed in the compartment or inclosure formed by the cover and its pivoted side-sections. 125

7. A toy book having covers, and leaves pivoted therein in book-fashion, and one of said covers having pivoted side-sections adapted to be swung out at right-angles, and means for holding the side-sections in unfolded position. and means for holding the leaves successively raised. 35
8. A toy book having covers, and leaves pivoted therein in book-fashion, one of said covers having pivoted side-sections adapted to be swung out at right-angles, and a strip adapted to connect the two side-sections of the cover and hold the same in unfolded position. 40
9. A toy book having covers, and leaves pivoted therein in book-fashion, one of said covers having pivoted side-sections adapted to swing out at right-angles thereto, and connecting-strips adapted to engage the side-sections at their upper and lower edges for holding said sections in unfolded position. 45
10. A toy book having leaves pivoted in book-fashion, said leaves having representations on both sides, that on one side of one leaf being related to that on one side of the adjacent leaf, and means for holding the leaves successively raised. 50
11. A toy book having leaves pivoted in book-fashion, said leaves having representations on both sides, that on one side of one leaf, except the outside leaf being related to that on one side of the adjacent leaf, the outside leaf having on its outer side the representation of the exterior of a building, 55
12. A toy comprising two members pivoted together at one edge so that one may be swung at right angles to the other, one of said members having pivoted side-sections adapted to be moved out at right-angles thereto when said members are opened at right angles to each other to form an inclosure, the member and its side-sections carrying upon both sides representations, that upon one of the faces of the side-sections being related to that upon the same side of the member to which said sections are pivoted and that upon the opposite face of the side-sections being related to that on the opposite side of said member. 60
13. A toy comprising two members pivoted together at one edge so that one may be swung at right angles to the other, one of said members having pivoted side-sections adapted to be moved out at right-angles thereto when said members are opened at right-angles to each other, to form an inclosure, in combination with a member having cut-out representations adapted to be disposed in said inclosure. 65

In testimony whereof I affix my signature in the presence of two witnesses.
